BAKING MOLD

Wayne W. Perry, 2291 Kendall St., Edgewater, Colo.

Filed Oct. 18, 1965, Ser. No. 87,568

Term of patent 14 years

(Cl. D44—1)

FIG. 1

FIG. 3

FIG. 1 is an exploded perspective view of a baking mold embodying my new design.

FIG. 2 is a front elevational view thereof in assembled condition; and

FIG. 3 is an end elevational view.

I claim:

The ornamental design for a baking mold, substantially as shown.
